UNITED STATES PATENT OFFICE

162,608

RADIO-TELEVISION RECEIVER AND PHONOGRAPH CABINET

Samuel E. Adler, Chicago, Ill.

Application January 21, 1949, Serial No. 375

Term of patent 14 years

(Cl. D56—4)

To all whom it may concern:

Be it known that I, Samuel E. Adler, a citizen of the United States and resident of Chicago, in the county of Cook, State of Illinois, have invented a new, original, and ornamental Design for a Radio-Television Receiver and Phonograph Cabinet, of which the following is a specification, reference being had to the accompanying drawings, forming a part thereof.

The figure is a front perspective view of a radio-television receiver and phonograph cabinet, showing my new design;

The dominant features of my design reside in the front panel of the cabinet.

I claim:

The ornamental design for a radio-television receiver and phonograph cabinet, substantially as shown and described.

SAMUEL E. ADLER.
